United States Patent Office.

THOMAS W. BROWN, OF READING, PENNSYLVANIA.

Letters Patent No. 91,514, dated June 22, 1869.

IMPROVEMENT IN GRINDSTONE-JOURNAL BOX.

The Schedule referred to in these Letters Patent and making part of the same.

To all persons to whom these presents may come:

Be it known that I, THOMAS W. BROWN, of Reading, of the county of Berks, and State of Pennsylvania, have invented an Improved Grindstone-Journal Box; and do hereby declare the same to be fully described in the following specification, and represented in the accompanying drawings, of which—

Figure 1 is a top view,

Figure 2, a side elevation,

Figure 3, a longitudinal section of it.

Figure 4 is a top view of it as it appears with its cover raised.

Figure 5 is a transverse section of it taken through the journals of one of its friction-wheels.

On October 16, 1866, Letters Patent, No. 58,768, were granted to me on a grindstone-journal box.

My present box, like that on which the patent was granted, contains two friction-rollers, on and between the peripheries of which the grindstone-journal, when supported by and arranged in the box, immediately rests.

It is well known to be of great importance to protect both the circumferences, the journals, and bearings of each of the friction-rollers, from water and sand, or grit thrown off by the grindstone while in use, otherwise the rollers and their journals, as well as the journal of the grindstone, would soon become worn or seriously impaired by such.

My patented box contained provision for so protecting the friction-wheels, their journals, and bearings, as well as the grindstone-journal, when supported by the said wheels.

This is also the case with my present box, but in the latter I have made an important improvement, which consists in arranging the friction-wheel journals, and bearings, and abutments, wholly within the oil or wheel-chamber, and underneath its cap or cover.

My patented box, as above referred to, was furnished with wheel-journal caps, combined with the cover, and projected from its opposite outer sides, so as to extend over and about the upper parts, and the ends of the wheel-journals supported in bearings arranged outside of the wheel-chamber, and at the sides of the box.

In carrying out my present improvement, I dispense with such journal-caps, and the particular arrangement of them as mentioned, and I arrange the wheel-bearings and journals, and the abutments thereof, wholly within the wheel-chamber of the box, and cover the wheels, their journals and bearings, and the whole wheel-chamber, by an arched or other properly shaped cover, made to extend over the whole of the

top of the latter, and hinged to the oil-reservoir of the box.

In the drawings—

A denotes the oil-reservoir or receptacle, and B its cover, the two being provided with semicircular notches x y , at their middles, to admit a grindstone-journal to extend laterally through the box, and between, and rest upon the peripheries of the two friction-wheels C C.

These wheels, with their journals a a , are arranged wholly within the oil-cistern or chamber b , of the box, and their bearings c c are fixed or cast upon the inner opposite sides of such chamber, such sides serving also as abutments for the outer ends of the journals.

By having the journal-boxes within the wheel-chamber, so as to be covered by the cap or cover thereof, I avoid the necessity of caps to them, such as are used in my patented box, and which are liable to become broken off the cover. Besides I very much better protect the wheel-journals from the sand and grit which may be discharged from the wheel; and what is better, I effect a saving of oil, which, with my other box, is liable to waste out of the bearings of the journals, and run down on the outer sides of the box.

I herein make no claim to the broad principle of making a grindstone-journal box with two bearing-wheels and an oil-reservoir, with the journal-bearings of the wheels formed on the sides of the reservoir.

Nor do I claim arranging the journal-bearings outside of the box, and providing the cover with chambered caps or projections, to extend over such bearings and the journals, and lap on the ends of the latter, so as to constitute protections and abutments therefor; this latter mode of making a grindstone-journal box being described in and covered by my said patent.

What I claim as my present invention, is—

The improved manufacture or grindstone-journal box, as made with the friction-wheel bearings and journals, and journal-abutments, arranged wholly within the oil-receptacle, and with the bearings projecting inward from its opposite sides, in combination with the cover, arranged and constructed so as, when shut down upon the oil-receptacle, it shall close it, and extend over the wheels, their bearings, journals, and journal-abutments, in manner substantially as above described, and as represented in the accompanying drawings.
